UNITED STATES PATENT OFFICE

2,435,297

DISPENSER FOR MATCHES AND THE LIKE

Loren Thomas and Ladford Bell,
Port Huron, Mich.

Application March 5, 1947, Serial No. 732,433

1. Claim. (Cl. 312—84)

1.

The present invention relates to improvements in dispensers for matches, particularly of the so-called "kitchen match" type which can be ignited by striking them on any dry surface or for cigarettes, or tooth picks, or other small longitudinal articles.

One object of the present invention is the provision of a device of the character described which is mechanically operated and is specifically constructed as a safety device, in that no matches or the like are exposed to the view, especially to children.

Another object of the present invention is the provision of a device of the character described which is adapted to be placed on a wall and to eject matches or the like as needed without making it necessary to open the device for taking a match or the like therefrom.

Still another object of the present invention is the provision of a device of the character described which can be replenished easily and within the shortest possible period of time.

Yet a still further object of the present invention is the provision of a device of the character described which is light in weight and simple in construction, consisting of only a few inexpensive parts that can be assembled easily and without the application of any considerable amount of skill, but which is of a pleasing appearance, sturdy, durable, and well adapted to withstand the rough usage to which devices of this type are frequently subjected.

With the foregoing and other objects in view which will appear as the description proceeds, the invention consists of certain novel details of construction and combinations of parts herein-after more fully described and pointed out in the claim, it being understood that changes may be made in the construction and arrangement of parts without departing from the spirit of the invention as claimed.

In the accompanying drawings the preferred forms of the invention have been shown.

In said drawings:

Figure 1 is a side elevation of a preferred embodiment of our invention;

Figure 2 is a front elevation of the same; and

Figure 3 is a sectional view on the line 3—3 of Figure 2.

Similar reference characters refer to similar parts throughout the several views.

In the drawing the numeral 1 denotes an upright container which has a stationary rear wall 2 and stationary side walls 3. The top and the front of the container 1 are normally closed by

means of an angular lid 4, which preferably is secured to a shaft 5 that is rotatably fastened to the lower portions of the side walls 3, so that the front as well as the top of the container 1 can be opened by swinging the lid 4 open as indicated in dash and dotted lines in Figure 1. This arrangement allows a quick and easy refilling of the container with matches or the like to replenish those used. The lid 4 can be moved angularly more than ninety degrees, thus making the entire interior of the container 1 accessible.

In the lower portion of the container 1 there is rotatably arranged a drum 6 whose periphery is provided with longitudinal horizontal grooves 7. The axial portion of the drum 6 is connected to knobs 8, preferably by means of shafts 9 which are extended through the knobs 8 and the side walls 3 into the drum 6, the shafts 9 fitting tightly into the drum 6 and the knobs 8. This arrangement is preferred because it facilitates the assembly work of our new and improved device, but it will be understood that the drum 6 can be connected to the knobs outside of the container 1 also by any other suitable means.

A block 10, whose lower portion is wedge-shaped and whose upper portion is bulged outwardly, is secured to the inner side of the rear wall 2 in such a manner that its wedge-shaped portion is closely above the drum 6. The upper portion of the block 10 is provided with an inclined slot 11 which is in alignment with, and has the same inclination as, the inclined front surface 12 of the block 10. A plate 14, whose lower portion is rolled rearwardly and incloses a pin 15, is provided with slots 16 in its upper portion, and the latter is slideable in the slot 11. Pins 17 are extended through the upper portion of the block 10 and the slots 16 as well as into the rear wall 2, so as to limit the movement of the plate 14 and to secure the block 10 to the rear wall 2 as well. A slide 20 having an upwardly curved lower portion is secured to the lower section of the casing 1 and is extended into the latter up to the junction of the block 10 and the rear wall 2, as may be seen in Figure 3. The slide 20 is as wide as the container 1, but from that portion of the slide 20 which extends into the container 1 there are cut out the outer side portions 21, and said side portions 21 are secured to the lower extremities of the side walls 3 by means of nails 22 or in any other suitable manner, thus providing a simple and inexpensive means for fastening the slide 20 to the container 1.

The upper portion of the rear wall 2 preferably is provided with a hanger 23 for the purpose of

facilitating the fastening of the device to a wall.

The operation of our new and improved dispenser is as follows: When that portion of the container 1 which is above the drum 6 has been filled, for instance with matches which are horizontally arranged therein, the device is suspended from a nail (not shown) on a wall; then the matches as well as the lower portion of the plate 14, by means of gravity, are forced against the periphery of the drum 6, and at least one match will normally lay in one of the grooves 7; upon turning one of the knobs 8 in a clock-wise direction, the rotation of the drum 6 will move the match which is in the groove 7 towards the slide 20, and after a movement of the drum 6 of about one hundred and eighty degrees, the match will fall out of the groove 7 into the upwardly curved lower end portion of the slide 20, from where it can be taken without opening the lid 4. The lower portion of the plate 14, which normally rests against the drum 6, acts as an automatic shutter preventing that more than one match at a time be ejected. Should some of the matches accidentally be in a position in which they cannot glide properly into a groove 7, the knob 8 is turned first in an anticlockwise direction and then in a clockwise direction, which will be sufficient for bringing the matches which are adjoining the drum 6 into the proper position.

If the device is to be used for ejecting and storing other articles than matches, the only alteration necessary is the exchange of the drum 6, so that a drum whose grooves 7 are so dimensioned that they can hold one cigarette or similar article is used.

Since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claim is intended to cover all of the generic and specific features of the invention herein described, and all statements of the scope of the invention

which as a matter of language might be said to fall therebetween.

Having thus fully described our said invention, what we claim as new and desire to secure by Letters Patent is:

A device of the character described comprising an upright container whose rear wall and side walls are stationary and whose front and top walls are formed as a rectangular lid which is 10 pivotally connected to the lower portions of the side walls, a drum having a longitudinally grooved periphery and being rotatably arranged in the lower portion of said container and connected to knobs which are outside of said side walls, a block being secured to said rear wall adjacent said drum and having a wedge-shaped lower portion and an outwardly bulged upper portion into which extends an inclined slot which is in alignment with the inclined outer surface 15 of said wedge-shaped portion, a plate having a rearwardly rolled lower edge portion and being vertically slidable on the inclined surface of said block and adapted to rest normally against said drum, and a downwardly inclined slide having an 20 upwardly curved lower portion and being secured to and protruding over the lower section of said container adjacent said drum and extending within said container up to the juncture of said block and said rear wall, the width of said drum, 25 said block and said plate being slightly less than the distance between the inner sides of said side walls, all substantially as described.

LOREN THOMAS.
LADFORD BELL.
